BABY'S TOY

Eleanore Matthews, West Branch, Mich.

Application December 12, 1956, Serial No. 44,162

Term of patent 14 years

(Cl. D34—15)

Fig. 1 is a front elevational view of a baby's toy, showing my new design.

Fig. 2 is a fragmentary front elevational view thereof, to an enlarged scale, showing the end link.

Fig. 3 is a fragmentary side elevational view thereof, to an enlarged scale, showing the end link, and

Fig. 4 is a side elevational view thereof.

The broken line showing of a hand in Fig. 1 is for illustrative purposes only.

I claim:

The ornamental design for a baby's toy, as shown and described.
